J. CARR

PRINTING MACHINE

Filed Aug. 8. 1924

WITNESS
H. H. Thurst.

BY *Denison & Thompson*
ATTORNEYS

UNITED STATES PATENT OFFICE.

JAMES CARR, OF SYRACUSE, NEW YORK.

PRINTING MACHINE.

Application filed August 8, 1924. Serial No. 730,848.

To all whom it may concern:

Be it known that I, JAMES CARR, a citizen of the United States of America, and a resident of Syracuse, in the county of Onondaga, in the State of New York, have invented new and useful Improvements in Printing Machines, of which the following, taken in connection with the accompanying drawings, is a full, clear, and exact description.

This invention relates to a machine for printing identification tags as used more particularly on key rings, hand bags, and other articles which it may be desired to label with the name and address of the owner for identification.

These tags are usually made of non-corrodible sheet metal, and the names and addresses of the owner are usually printed thereon with steel dies for permanency of impression, and the main object of this invention is to provide a simple, compact and efficient machine for expeditiously printing the various letters and number of the name and address of the owner in uniformly spaced relation and in one or more lines upon the tag.

Another object is to provide means for automatically shifting the tag longitudinally along each line for proper spacing of the letters and numbers.

A further object is to provide means for adjusting the tag holder transversely relatively to the die-operating member for printing in parallel spaced lines upon the tag.

Other objects and uses relating to specific parts of the machine will be brought out in the following description.

In the drawings:

Figure 1 is a perspective view of one construction of machine for carrying out the object stated.

Figure 2 is an enlarged longitudinal vertical sectional view of the same machine taken on line 2—2, Figure 1, except that the upper portion of the plunger is broken away.

Figure 3 is a perspective view of a tag to be printed.

Figure 4 is a horizontal sectional view taken in the plane of line 4—4, Figure 2.

Figure 5 is a detail vertical sectional view taken in the plane of line 5—5, Figure 4.

As illustrated, this machine comprises:

base —1— having a central upright post 55 —2—, the upper portion of which forms a tubular guide for a vertically movable plunger —3— having at its upper end, a handle —4— by which it may be depressed by hand against the action of a retracting spring —5—.

The base —1— is substantially flat and adapted to rest upon a bench or other suitable support for holding the machine in an upright position and is disposed in a plane at right angles to the axis of the guide tube —2— and plunger —3—, said base being provided along its front edge with an upstanding guide flange —6— extending longitudinally in a straight line some distance in front of the produced axis of the plunger —3— for engaging the front edge of a horizontally movable carriage —7— and guiding the same in its longitudinal movement.

The base —1— is also provided with a pair of raised hollow bosses —8— at the rear of the carriage —7— for receiving a pair of yielding friction members —9— and a pair of coil springs —10— which serve to press the friction members —9— against the rear edge of the carriage for holding the front edge of the carriage in frictional engagement with the flange —6— and thereby permitting free longitudinal movement of 85 said carriage and at the same time preventing excessive movement thereof by its operating means presently described.

A tag-holder —11— is movable transversely of and upon the carriage —7— at 90 right angles to the plane of movement thereof for receiving and supporting a tag as —A—, Figure 3, and for this purpose is provided on its underside with a transverse rib —12— movable in a corresponding 95 groove —13— in the upper face of the carriage —7— and is also provided on its underside with a downwardly projecting pin —14— adapted to enter any one of a plurality of, in this instance, three transversely aligned apertures —15— which are arranged in transversely spaced relation corresponding to the three printing spaces —a— in the blank tag, as shown in Figure 3.

This transverse adjustment of the tag holder for line spacing of the printing is accomplished by lifting the holder to disengage its pin —14— from one aperture

and then moving it transversely to register the pin with another aperture and afterward lowering the plate to cause the pin to enter the registering aperture for assisting the guide, this operation being effected by hand, while the rib —12— in the guide groove —13— serves to keep the holder in proper transverse alinement relatively to the carriage.

10 Suitable means is also provided for clamping and releasing the tag upon and from the holder, and for this purpose, the rear edge of the plate is provided with a raised flange —16— having an end stop —17—, said plate —11— being also provided with an upright post or bearing —18— upon which is mounted, a rotary eccentric —19— adapted to engage in an aperture in the adjacent portion of a clamping plate —20—, Figure 5.

This clamping plate rests upon the upper face of the plate —11— in front of the flange —16— and stop —17— leaving sufficient space when the clamping plate is withdrawn by the proper rotation of the eccentric —19— to permit the tag —A— to be inserted in said space lengthwise of the carriage and flatwise upon the upper face of the plate between the flange —16— and rear edge of the clamping member —20— so that when the tag is properly placed for printing, it may be clamped in position by the rotary adjustment of the eccentric —19—, which in turn, tightly impinges the tag between the rear edge of the clamping plate —20— and flange —17—, the eccentric —19— being provided with a knurled handle by which it may be rotated by hand and at the will of the operator.

40 The plate —11— is also provided with a pair of lugs —21— rising therefrom at opposite sides of the clamping plate —20— for holding the latter against lateral movement while permitting it to be moved forwardly and rearwardly.

It will now be understood that the carriage —7—, plate —11— and clamping member —20— are movable in parallel planes at right angles to the axis of the plunger —3— and that when the tag is properly clamped in place for printing, it will also be disposed in a horizontal plane at right angles to said axis.

55 The means for setting the carriage —7— and parts carried thereby transversely of the axis of the plunger for letter and number spacing consists, in this instance, of a toothed rack —22— rigidly secured to the upper face of the carriage near the rear edge thereof to be engaged by a pawl —23— on the lower end of a rock arm or lever —24— which is pivoted intermediate its ends at —25— to the upright post —2— and has its upper end provided with a pivoted abutment —26— adapted to be engaged by

a stud or shoulder —27— on said post as shown in Figure 2.

The pawl —23— is pivoted at —28— to the lower end of the lever —24— and is yieldingly held in engagement with the teeth of the rack —22— by means of a spring —29—, said pawl being also provided with a handle —30— by which it may be tripped at will when it is desired to set the carriage at any particular point relatively to the printing die as shown by dotted lines in Figure 2.

75 A spring —31— is interposed between the lower portion of the lever —24— and adjacent side of the post —2— between the pivots —25— and —28— for retracting the lower end of the lever and pawl carried thereby after each downward movement of the plunger which operates the lever to feed the carriage in this instance, from the right 80 to the left hand of Figure 2, one tooth space at a time.

The abutment —26— is pivoted at —33— to the upper end of the lever —24— to permit its inner end to swing downwardly independently of the lever by the engagement of the pin —27— therewith when the plunger is depressed, but is extended outwardly some distance beyond its pivot for engagement with a pin —34— on said lever 95 to limit the upward movement of its inner end and thereby to cause the pin —27— to move the upper end of the lever outwardly and its lower end inwardly for feeding the carriage one tooth space at each upward 100 movement of the plunger after the latter has operated the die —B— to make the desired impression upon the tag —A—.

A spring —35— is connectel to the inner end of the member —26— for yieldingly 105 holding its outer end in engagement with the pin —34—.

The stud —27— preferably consists of a screw engaging in the threads —27— in the plunger —3— to permit it to be adjusted 110 for regulating the movement of the lever —24— and thereby regulating the amount of movement of the pawl —23— and carriage —7— following each printing operation.

115 The type bars —B— are placed by hand in an upright position against a pair of shoulders —36— with their lower ends resting upon the upper surface of the tag to be printed, said shoulder being rigidly secured in vertically spaced relation to the plate —37— which in turn is secured to the post —2— just above the work holder —11—.

The plate —37— and shoulders —36— 120 form respectively, a back rest and a side rest and constitute a guide for the type bar —B— and are set in such relation as to support the type bar directly under the lower end of the plunger —3— when the latter is elevated so as to be engaged there- 125 130

by when depressed for producing the printing impression on the tag.

Operation.

5 The blank tags —A— are placed upon the holder —11— against the shoulders —16— and —17— and clamped in place by the clamping plate —20— and if the impressions are to be made in the first line 10 space, the holder —11— is adjusted with its pin —14— in the outermost aperture —15— and the carriage —7— is moved to the right to the proper position to print the first letter of number at the left hand end of the 15 first printing space on the tag.

Each type bar bearing the letter, number or other character to be impressed upon the tag is placed by hand against the shoulders —36— with its lower printing end resting 20 upon the tag whereupon the plunger —3— is depressed by hand to engage the upper end of the die and to force its printing face against the underlying tag with sufficient force to make its impression therein.

25 During this downward movement of the plunger, the inner end of the abutment —26— will be depressed against the action of its retracting spring —35— by the stud —27—, which by the downward movement 30 of the plunger, is moved below the member —26— without disturbing the position of the lever —24— but upon the return upward movement of said plunger by the spring —5—, the engagement of the stud —27— with the underside of the abutment —26— will cause the lower end of the lever —24— and its pawl —23— to be rocked inwardly toward the axis of the plunger a sufficient distance to move the carriage 40 —27— one tooth space, thereby moving the blank tag —A— one letter or number space ready for a repetition of the printing operation by placing another type bar in operative position against the shoulders 45 —36—, these operations being repeated along the line of the tag operated upon.

If it is desired to print in the next line space, the work holder —11— is shifted inwardly toward the axis of the plunger

from one aperture —15— to the next adjacent aperture whereupon the successive printing operations may be performed upon the corresponding line of the tag and when this work is completed, the holder may be again shifted to the next aperture —15— to 55 print upon the third line in the manner previously described.

When the printing operations are completed as for example, the name in one line, the street and number or town in the 60 next line, and the state in the third line, the plate may be withdrawn by hand by simply releasing the clamping plate —20—.

I claim:

1. In a machine for printing identification tags and the like, a main supporting base, a carriage slideable horizontally upon the base for letter spacing, a work-support mounted on the carriage to move therewith and having an independent adjustment 65 transversely thereof for line spacing, a type bar guide in fixed relation to the carriage, a removable type bar insertable by hand to rest against the guide with its printing face adjacent the work on the support, means 70 for operating the type bar to make its impression upon the work, and means for sliding the carriage step by step lengthwise of and upon the base.

2. In a machine of the character described, a main supporting base, a carriage slideable horizontally upon the base, a work support mounted on the carriage to move therewith and having an independent adjustment transversely thereof for line spacing, a type bar rest in fixed relation to the carriage, a type bar adapted to be placed by hand against the rest with its printing face adjacent the work on the support, a plunger for operating the type bar, means 80 for retracting the plunger, and means actuated by the retraction of the plunger for feeding the carriage longitudinally for character spacing.

In witness whereof I have hereunto set 85 my hand this 26th day of July, 1924.

JAMES CARR.
